(57) CLAIM

The ornamental design for an optical apparatus container, as shown and described.

DESCRIPTION

FIG. 1 is a top, front, left side perspective view of an optical apparatus container, showing my new design;

FIG. 2 is a front elevational view thereof;

FIG. 3 is a back elevational view thereof;

FIG. 4 is a left side elevational view thereof;

FIG. 5 is a ride side elevational view thereof;

FIG. 6 is a top plan view thereof;

FIG. 7 is a bottom plan view thereof; and,

FIG. 8 is a front elevational view thereof, shown in open condition with unclaimed optical apparatus is shown in use.

The broken lines shown in the drawings are for illustrative purposes only and form no part of the claimed design.
